T. P. BRENNY

HALTER

Filed Dec. 17, 1925

Inventor

T. P. BRENNY

By Clarence O'Brien

Attorney

UNITED STATES PATENT OFFICE.

THOMAS P. BRENNY, OF FOLEY, MINNESOTA.

HALTER.

Application filed December 17, 1925. Serial No. 75,996.

To all whom it may concern:

Be it known that I, THOMAS P. BRENNY, a citizen of the United States, residing at Foley, in the county of Benton and State of Minnesota, have invented certain new and useful Improvements in Halters, of which the following is a specification.

My present invention pertains to halters; and it has for its object the provision of a 10 halter of simple and inexpensive construction, capable of ready manipulation for application and removal and possessed of many practical advantages in other respects.

My invention also contemplates the provision of a halter susceptible of being formed entirely of a single length of appropriate rope, without the employment of any extraneous devices whatsoever, and in such manner that the contacting portions of the 20 rope are utilized to afford the necessary frictional contact to prevent casual loosening of the halter on the head of an animal.

Other objects and practical advantages of the invention will be fully understood from 25 the following description and claims when the same are read in connection with the drawings, accompanying and forming part of this specification, in which:—

Figure 1 is a view illustrative of the halter 30 constituting the best practical embodiment of my invention of which I am cognizant, applied to the head of an animal.

Figure 2 is an enlarged broken perspective of the preferred embodiment of my invention per se.

Similar numerals of reference designate corresponding parts in both views of the drawings.

As above indicated the preferred embodiment of my invention is formed of a single length of rope designated by 1. One end 2 of the rope is braided, and the rope is shaped as shown to form a head stall 3 with cheek portions 4, a nose band 5, and a 45 chin portion 6. One of the cheek portions 4 terminates in a loop 7, the said loop 7 being formed by interlacing of portions of the rope lengths as designated by 8. The chin portion 5 extends from the said interlaced or interlocked portions, and is provided with an intermediate loop 9 and an end loop 10, the said loops 10 and 9 being formed by interlacing portions of the rope lengths at the points 11 and 12, Figure 2. The other 55 cheek portion 4 is passed loosely through the intermediate loop 9, the end loop 7, and the

end loop 10, in the order named, and hence it will be manifest that when the free end portion of the length of rope is pulled upon, the nose band 5 and the head stall 3 will be 60 tightened upon the head of the animal, and the stronger the pull exerted on the said free end portion, the more tightly will the halter be bound upon the head of the animal. It will also be manifest that being formed of 65 rope the halter will be characterized by a considerable degree of frictional contact between the loop portions and the rope length passed through the said loops, and in consequence there is little or no liability of the 70 head stall, nose band or chin latch becoming casually loose even when no pull is exerted on the free end portion, and, therefore, there is no liability of an animal being able to free itself from the halter.

In addition to the foregoing advantages peculiar to my novel halter, it will be noted that the double loops including the loops 9 and 10 at one side of the nose band 5 prevent slipping of the head stall so that there 80 is no liability of the animal being choked by the chin latch formed by the passage of the rope length through the loops 7 and 10, in the order named.

When desired the halter may be converted 85 into a lasso by simply withdrawing the rope length from the loops 10, 7 and 9, and then passing the rope length through the loop 10 alone. Again the halter may be used around the neck of an animal by extending 90 the rope length after withdrawal of the same from the loops 10, 7 and 9 through the loop 7 alone or by inserting the center loop in the first or second end loops and then passing the rope through the center loop.

While I have described the preferred embodiment of my invention in detail, I do not desire to be understood as confining myself to all of the specific characteristics set forth, my invention being defined by my 100 appended claims within the scope of which changes in structure and arrangement may be made without departure from my invention.

Having described my invention, what I 105 claim and desire to secure by Letters Patent, is:—

1. A halter formed of a single length of rope and having a head stall, a nose band, and a chin latch; one of the cheek portions 110 of the head stall being provided with an end loop and with interlaced portion immediate-

- ly above the said end loop, and the nose band being merged into said interlaced portion and being merged, in turn, and provided with an intermediate loop and with an end loop, and
- 5 the other cheek portion of the head stall being passed through the said intermediate loop of the chin latch and being also passed through the first named end loop and the second named end loop in the order named.
- 10 2. A halter comprising a head stall, with cheek portions one of which terminates in a loop and the other of which terminates in a rope length, a nose band extending from the first-named cheek portion adjacent to
- 15 the loop thereof and provided with an intermediate loop and an end loop, and a chin

latch formed by the said rope length passed through the intermediate loop, the first named end loop, and the second named end loop in the sequence indicated.

3. A halter including a head stall, with cheek portions, a loop forming the terminal of one cheek portion, and a nose band extending from said cheek portion adjacent to said loop and having an intermediate 25 end portion adapted in conjunction with the first-named loop for the reception and play of a length of the material of which the halter is formed.

In testimony whereof I affix my signature.

THOMAS P. BRENNY.
